UNITED STATES PATENT OFFICE.

JOHN LEWIS, OF ELIZABETH, NEW JERSEY.

ATTACHING SAILS TO SHIPS' YARDS.

Specification of Letters Patent No. 30,582, dated November 6, 1860.

To all whom it may concern:

Be it known that I, JOHN LEWIS, of Elizabeth, in the county of Essex and State of New Jersey, have invented, made, and applied to use a certain new and useful Improvement in Attaching Sails to Spars; and I do hereby declare that the following is a full, clear, and exact description of the nature of my said invention, reference being had to the annexed drawing, making part of this specification, wherein—

Figure 1, is a plan of a portion of a spar with my means fitted thereto for attaching the sail. Fig. 2, is a section of the spar showing the chain ear-ring. Fig. 3, is a section of my clamp, and Fig. 4, is a section of my hasp.

Similar marks of reference denote the same parts.

In attaching sails to yards it is usual to have a rod on the upper side of the yard, and in bending the sails they are secured to this rod by seizings; a second rod is provided to form a reefing jack stay. This mode of attaching the sails involves considerable trouble and expense in bending the sails, and no ready means is furnished for detaching the sail when in port or when otherwise necessary.

The nature of my said invention consists in a series of movable clamps secured to the yard or other spar, and receiving the head rope of the sail and also in a movable and adjustable ear-ring that takes the angle or corner of the sail and holds the same firmly to the yard or spar.

In the drawing *a*, is a portion of a yard or spar and *b*, represents one corner of a sail.

c, is my improved clamp that is to be applied along on the yard or spar, at convenient and suitable distances apart. It is however preferable to place these clamps so as to take the head or inclosing rope of the sail where there is a seam in the canvas. Each of these clamps is attached by a screw bolt *d*, passing nearly through the center thereof and having a head, as seen in Fig. 3, that presses at the point 2, over the curved hollow toe piece 3 that receives the head rope of the sail so as to clamp the same firmly to the spar.

The rear or heel of the clamp rests on the spar, and is provided with eyes 1, 1, through which a life line *e*, is passed, or

the same may receive a reefing rod in the same position, so as to dispense with the separate reefing jack stay heretofore in use for reefing the sails. The bolt *d* setting into a socket in the clamp *c*, as represented allows for disconnecting the sail by simply turning said bolt *d* by a marline spike inserted into the eye thereof, and the T head of said bolt coming into this socket or recess allows the toe part 3 of the clamp to be raised and the head rope entirely freed, which is a great convenience as the clamps *c*, do not require disconnecting from the spar.

The thimble *g* in the corner of the sail is fitted as usual, and to this I connect my ear-ring by means of the hasp *f*. The ear-ring is formed of the chain *h*, at one end of which is the metal box *i*, containing a nut that takes the screw *m*, passing through the fork catch *h*. This fork catch *h*, is made as an open or skeleton connection; at the part 7 is a fork taking the link of the chain as said chain is passed around the spar, and by this chain my ear-ring can be adapted to any size of yard or spar, and clamped firmly thereto by the screw *m*, after the proper link of the chain has been dropped into the said fork 7; at 8, on this catch *h*, is a rib running longitudinally of the spar and taking a groove made therein so that the ear-ring cannot turn on the spar. The clasp *h*, also receives one end of the hasp *f*, that is formed to take the sail thimble *g* and fitted so that the upper part *f'*, can be opened on the joint 6, for entering or withdrawing the said thimble *g*, and when the parts *f*, *f'*, are shut together the stud 5 takes the strain and the button 4 secures the hasp together.

It will now be apparent that my device not only secures the sail very firmly to the spar, but that it furnishes facility for easily disconnecting the same and that without the cost of the seizings heretofore required whenever the sails were to be bent, and my ear-ring is adapted to different spars or different parts of the same spar, and is easily adjusted and secured in place.

What I claim and desire to secure by Letters Patent is—

1. The clamps *c*, *c*, fitted and acting substantially as set forth to retain the sail to the yard or spar, or allow of its being disconnected as specified.

2. The ear-ring formed of the chain *f*,

fork *h*, and screw *m*, to firmly clamp or grasp the yard or spar regardless of the seize as set forth.

3. The hasp, (*f*, *f'*), in combination with the ear-ring in the manner and for the purposes specified.

In witness whereof I have hereunto set

my signature this eighteenth day of October 1860.

JOHN LEWIS.
